UNITED STATES PATENT OFFICE.

WILLIAM THOMPSON, OF KALAMAZOO, AND GEORGE W. COPE, OF DETROIT, MICHIGAN,
ASSIGNORS TO KALAMAZOO STOVE CO., OF KALAMAZOO, MICHIGAN.

DESIGN FOR A HEATING AND COOKING STOVE.

No. 38,896.

Specification for Design.

Patented Nov. 19, 1907.

Application filed September 23, 1907. Serial No. 394,251. Term of patent 14 years.

To all whom it may concern:

Be it known that we, WILLIAM THOMPSON, a citizen of the United States, residing in the city and county of Kalamazoo, State of Michigan, and GEORGE W. COPE, a citizen of the United States, residing in the city of Detroit, county of Wayne, State of Michigan, have invented a new, original, and ornamental Design for a Heating and Cooking Stove.

Our new, original and ornamental design for a heating and cooking stove is illustrated in the accompanying drawing, which is a perspective view thereof.

We claim:

The ornamental design for a heating and cooking stove, substantially as shown.

WILLIAM THOMPSON.
GEORGE W. COPE.
